Albert M. Austin

ATTORNEY

UNITED STATES PATENT OFFICE.

GEORGE F. LONG, OF NEW YORK, N. Y., ASSIGNOR, BY MESNE ASSIGNMENTS, TO STEINER ELECTRIC CORPORATION, OF LONG ISLAND CITY, NEW YORK, A CORPORATION OF NEW YORK.

DASHBOARD CONTROL.

Application filed October 5, 1923. Serial No. 666,664.

This invention relates to controls for utilities adapted particularly for use where it is desired to operate a desired mechanism or utility from a distance.

- 5 One object of the present invention relates to the provision of means such as a Bowden wire operatively interconnecting the utility and the point at which it is to be controlled, of a handle or manually operated member, 10 a means cooperating with the handle and the interconnecting means so that movement in one direction of the handle operates the utility and movement in a different direction at an angle thereto locks the device.
- 15 In accordance with this object, there is provided simple and efficient means for permitting free movement of a member longitudinally but actuated by rotary movement thereto to lock the device in fixed position.
- 20 Various other objects and advantages of the invention will be in part obvious from an inspection of the accompanying drawings and in part will be more fully set forth in the following particular description of one 25 form of mechanism embodying my invention, and the invention also consists in certain new and novel features of construction and combination of parts hereinafter set forth and claimed.
- 30 In the accompanying drawings,

Figure 1 is a side elevation partly in section of one embodiment of my invention in place to operate a utility;

35 Figure 2 is a perspective view of one part of the mechanism of Figure 1; and

Figures 3 and 4 are sectional views taken on the lines 3—3 and 4—4, respectively, of Figure 1.

Referring to the drawings, there is shown 40 a dashboard 10, which may be the dash of a motor vehicle. Extending through the dash 10 is a casing 11 having a flanged end 12 in contact with the obverse face of the dash 10, an intermediate portion 13 and an end 45 portion 14 having a restricted diameter. Within the intermediate portion 13 is a recess which is tapered, the flare of the taper being towards the obverse of the dash 10. The other end of the recess is screw-threaded 50 for a purpose which will subsequently appear. The casing 11 is hollow and the interior is substantially symmetrical with respect to the longitudinal axis of the device, represented by the line 15—15 of Figure 1.

The face of the flange portion 12 is protected and embellished by a face plate 16, the edge of which may be spun over the edge of the flange. The flange 12 and face plate 16 are affixed to the dash 10 in any suitable manner, as by machine screws passing therethrough. The extreme end of the portion 14 of the casing 11 is provided with a screw-threaded boss 17 for the reception of a nipple or union 18 whereby a tube 19 is attached thereto. The end of the tube 19 is 65 preferably flared and the end of the boss 17 is slightly tapered, so as to hold the tube rigidly.

The tube 19 extends to a mechanism or utility to be operated. In the present instance this is shown as a muffler cut-out 20, such as used on motor vehicles, but it is understood that any device may be connected in like manner. Within the tube 19 is a wire 21, one end of which is connected to an operating lever or crank arm 22 of the device 20. The tube 19 in combination with the wire 21 forms collectively a so-called Bowden wire mechanism.

For controlling the actuation of the wire 21 and thus the movement of the arm 22 of the utility 20, there is provided a shaft member 30 loosely fitted within the casing, and having its inner end affixed to the end of the wire 21. The shaft member 30 has 85 two degrees of freedom within the casing 11, that is, it may be moved longitudinally or it may be rotated. It will be seen that this includes movement in one plane, i. e., the longitudinal plane of the device, as well 90 as movement in a plane at an angle to the first-named plane, i. e., a transverse plane of the device. The member 30 is preferably formed to have an asymmetrical cross-section with reference to the axial line 15—15; 95 that is, rotation of the member 30 about said axis produces unlike unbalanced motions of parts of its surfaces. A shaft of rectangular or square cross-section is suitable for the purpose.

For supporting the shaft member 30 to permit longitudinal movement and for locking the same in desired position there is provided a collet or jam member 40, which as clearly illustrated in Figure 2, comprises a 105 member having a screw-threaded shank 41 to fit the threads of the inner portion of the recess of the part 13 of the casing 11, and

having a tapering enlarged end 42 corresponding in configuration to that of said recess. The end 42 of the collet member 40 is split by means of a plurality of cuts such as 43, of which four are shown. Extending through the member 40 is an asymmetrical or rectangularly cut hole 44 of a size and shape to normally permit the shaft member 30 to pass therethrough freely. The collet member 40 is mounted on the shaft member 30 and is then screw-threaded into the recess of the part 13 of the casing 11, and when in the position shown in Figure 1 forms a supporting bearing for the shaft member 30. The outer end of the shaft member 30 is secured to a handle 45 in any suitable manner, as by being pinned thereto, so that any motion of the handle 45 is transmitted to the member 30.

20 In operation, assuming that the parts are in position as shown by the full lines of Figure 1, the crank 22 is in its fully closed position, or position with minimum opening of the utility 20, or other desired position of 25 the utility, and assuming that the device is not locked in that position, the operator grasps the handle 45 and pulls it out a desired amount, so that the crank of the utility is placed as may be desired, for example, in 30 the position shown by the dotted lines of Figure 1. When the control has been adjusted as desired, the handle 45 is rotated through a relatively small angle, and this rotary movement causes the shaft member 35 30 to rotate against the collet 40. The collet 40 is thus screwed inwardly and the wings 42 are severally pressed into intimate contact with the tapered walls of the recess. Continued rotary movement of the handle 40 through an additional angle will cause the shaft member 30, because of its characteristic cross-section, to wedge against the several wings of the collet 40, and thus jam them against the walls of the recess more 45 securely. The handle is maintained in the rotated position by the friction of the member 30 against the collet.

To readjust the utility 20, the handle 45 is again grasped, and is rotated in the contrary direction. The collet is thereby unscrewed and is thus caused to release the shaft 30. The handle is then moved into desired position and may again be locked as has been described.

55 Thus it will be seen that I have provided an efficient control for cut-outs, exhaust heater valves, testing valves, radiator shutters, carburetor air valves, or other desired

utilities, which is convenient and may be instantly unlocked and operated. The locking device maintains the utility in predetermined position, independent of vibration or vehicle sway. The device may be easily installed with a minimum of interference with other devices, such as gear shift levers or emergency brake levers. The handle serves as an indicating device for automatically indicating either by sight or touch, whether or not the device is locked.

While I have shown and described and 70 have pointed out in the annexed claims certain novel features of my invention it will be understood that various omissions, substitutions and changes in the form and details of the device illustrated and in its operation may be made by those skilled in the art without departing from the spirit of 75 my invention.

Having thus described my invention, I 80 claim:

A manual control for mechanism, comprising a casing having a hollow bore terminating in an enlarged recess, the outer portion of said recess being tapered inwardly and the inner portion thereof being provided with an internal screw thread, a single split collet positioned within said recess, said collet having an outer tapered portion and inner externally threaded portion adapted to cooperate with the corresponding portions of the recess in said casing, said collet being also provided with a central bore having an irregular contour; a longitudinally slid able member positioned within said collet, said member being adapted at one end for attachment to a mechanism operating means and being adapted at the other end for attachment to an actuating handle, said slid able member being entirely supported by said collet and being of a contour similar to that of the bore in said collet, whereby relative longitudinal movement is permitted and relative rotational movement prevented, said collet in one position thereof allowing free movement of said slid able member and being adapted when rotated in response to rotational movement of said slid able member to engage with the tapered walls of said recess and cooperate therewith to firmly lock said member against longitudinal movement.

Signed at New York in the county of Queens and State of New York this 1st day of October, A. D. 1923.

GEORGE F. LONG.
